SAFETY RAZOR BLADE

Filed Jan. 18, 1928

Martin T. Fisher Attorney

Merrill Anderson

UNITED STATES PATENT OFFICE

MERRILL ANDERSON, OF NEW YORK, N. Y.

SAFETY RAZOR BLADE

Application filed January 18, 1928. Serial No. 247,869.

This invention is in a safety razor blade, and represents an improvement over the safety razor blade shown in my copending application, Serial No. 214,167, filed August 19, 1927. The subject matter of this application is also related to my copending application, Serial No. 247,670, filed on even date herewith.

The invention here is a safety razor blade 10 of general rectangular shape, provided with two sharpened edges, and provided with two notches in each end of the blade, one near each corner thereof, so that it can be used with a razor of the self-stropping or "Auto-strop" type, shown, for example, in the patent to Gaisman No. 1,022,726, dated April 9, 1912 and also in patents 1,022,727, dated April 9, 1912 and 1,088,220, dated February 4, 1914.

By providing the blade with a notch in each 20 corner, and by providing two sharpened edges, the blade is readily reversible, so that its life is practically doubled.

The blade is also provided with shoulder lugs bent from the metal of the blade, which 25 are adapted to rest on the upper edge of a blade holder for limiting the inward movement of the blade with respect to the holder, so that the blade will not be forced too far into the holder and the sharp edge within the 30 holder thereby dulled.

Another feature of the invention is a blade holder, U-shaped in cross section and provided with flat gripping jaws. This holder is sufficiently stiff, so that it provides a rigid 35 backing for a thin metal blade and is sufficiently springy so as to firmly grip the blade between its jaws.

This blade holder is also provided with lugs, pressed from the metal of the holder, 40 which are adapted to snap into the notches in the corner of the blade, for holding the blade in the holder.

The blade, without its holder, may be used 45 in a safety razor of the self-stropping type and may be reversed after one edge is dull, to use the new edge, thereby doubling the life of the blade.

The blade, when mounted in the U-shaped holder above described, may be used in the 50 well known type of safety razor known as

the "Gem", as shown in Patent No. 1,018,783 dated 1912, to Scheuber.

There is thus provided a safety razor blade, which is readily capable of use in either of two widely known types of safety razors, 55 the "Auto-strop" and the "Gem" type, and moreover is provided with two sharpened edges, both of which are capable of use with either of these types of razors.

There is illustrated in the accompanying 60 drawings several ways of carrying out the invention; in these drawings,

Fig. 1 is a perspective view of one form of blade;

Fig. 2 shows this type of blade mounted in 65 an "Auto-strop" holder;

Fig. 3 is a perspective view of another type of blade;

Fig. 4 shows the blade of Fig. 3 in its 70 holder;

Figs. 5, 6 and 7 show modified forms of 75 blades and holders;

Fig. 8 shows the blade in position in a "Gem" razor; and

Fig. 9 is also a view of a modified form of 80 blade and holder.

Referring now to these drawings in which similar reference characters indicate similar parts, the blade 2 is of general rectangular form and is provided with sharpened edges 85 4 and 6, and with notches 8 and 10 in the ends of the blades near the corners. These notches preferably have straight parallel sides 10a and a curved inner part 10b.

The center portion of the blade may be cut 85 away as shown at 12, and the upper and lower edges of the cut-out portion bent laterally, forming flanges 14.

This blade is mounted in the standard 90 "Auto-strop" holder as shown in Fig. 2; this holder comprises the usual gripping jaws 16 and 18 and the usual members 20 and 20' which snap into the notches for holding the blade in place.

After one edge of the blade has been used, 95 the blade may be reversed and the sharp edge brought into position for shaving.

Referring now to Fig. 3, shoulders 22 are struck out from the metal of the blade; these shoulders are adapted to rest on the upper 100

edge of the gripping jaws of an "Auto-strop" razor, having the same mechanical effect, that of limiting the inward movement of the blade, as the flanges 14.

Either of the blades of Figs. 1 and 3 may be positioned in a U-shaped holder, and when so positioned, may be used in a safety razor of the "Gem" or "Everyready" type.

Referring to Fig. 4, a blade 24, of the type shown in Fig. 3, is positioned in a U-shaped holder, the holder having a pair of flat springy gripping jaws 26. Lugs 27, corresponding to lugs 22 of Fig. 3, rest on the top edge of the U-shaped holder, and serve to limit the inward movement of the blade with respect to the holder, and to provide a clearance 28, for protecting that sharp edge of the blade, which is within the holder.

Referring now to Fig. 5, the blade is provided with notches 8 and 10, as before. The U-shaped holder comprises flat springy gripping jaws 29 connected at the bend 30. The metal of the holder is struck inwardly to form projections 32, which are adapted to snap into the notches 8 or 10, and thus hold the blade in position in the holder so that there is a clearance 34 below the lower sharp edge, for preventing the dulling of that edge by contacting with the inside of the holder. With the blade in place in the holder as shown in Fig. 5, the blade may be used in a razor of the "Gem" type, as in Fig. 8. After one edge is dull, the blade may be readily reversed and the other sharp edge used.

In the blade shown in Fig. 6, shoulders or lugs 36 are pressed out of the metal of the blade, these shoulders being adapted to rest on the upper edge or edges of the U-shaped holder for limiting the inward movement of the blade with respect to the holder. Lugs 32 snap into the notches 8 and 10, as before, for further aiding in the accurate and secure holding of the blade. This form includes both the features of Figs. 4 and 5.

In the form shown in Fig. 7, the blade 38 is provided with notches 40 and is fitted into a U-shaped holder of the type already described, which has inwardly projecting lugs 32 snapped into the notches 40, for holding the blade in position.

The exposed notches 8 or 10, as the case may be, furnish gripping points useful in extracting the blade. The blade itself may be made of rustless steel, and may also be covered with water repellent grease, for preventing the rusting of the edge of the blade within the holder. The exposed shoulders 14, 22 and 36, also furnish gripping points useful in extracting the blade from the holder, preparatory to reversing the blade, or to the insertion of a fresh blade.

In Fig. 8, a blade of the type shown in Fig. 5 is shown in position in a razor of the "Gem" type, having the usual pivoted spring cover member 42 for clamping the blade in place.

Any of the blades of Figs. 4, 5, 6 or 7 could be used in this holder.

In the modification shown in Fig. 9, the U-shaped holder is provided with elongated lugs, pressed or cut from the body of the holder, and these lugs 43 snap into elongated slots 44 cut in the blade, for securing the blade in place.

While I have illustrated my invention in some detail, it should be understood that it is not to be limited to the precise details here shown, but may be carried out in other ways, as expressed within the scope of the claim.

I claim as my invention:

A safety razor blade made of thin metal, having two sharpened edges, and provided with a notch in each corner thereof, the notches opening endwise of the blade, the blade being further provided with a plurality of outstruck lugs adjacent the sharp edges of the blade, two of the notches serving to engage with a suitable holder, while the other two notches furnish exposed gripping points useful in extracting the blade from the holder, the outstruck lugs being adapted to rest on the upper edge of the holder for limiting the inward movement of the blade with respect to the holder.

In testimony whereof I affix my signature,

MERRILL ANDERSON.
